(57) **CLAIM**

The ornamental design for a battery, as shown and described.

DESCRIPTION

1.1 is a front view of a battery showing the new design;

1.2 is a back view thereof;

1.3 is a left side view thereof;

1.4 is a right side view thereof;

1.5 is a top view thereof;

1.6 is a bottom view thereof;

1.7 is a perspective view thereof; and

1.8 is a further perspective view thereof.

The broken lines in reproduction 1.6 are for the purpose of illustrating portions of the battery that form no part of the claimed design.
